SUBMARINE CABLE

Application filed September 4, 1928, Serial No. 303,970, and in Great Britain September 2, 1927.

It has not hitherto been considered possible to construct submarine cables permitting of telephonic communication over very great lengths. The submarine cables between Key West (Florida) and Habana (Cuba) of 5 length slightly in excess of 100 nautical miles are at present the longest affording channels for the electrical transmission of speech. Recent improvements in materials for the continuous loading of the conductor may have 10 foreshadowed an increase of this length by two or even three times, but the possibility of telephonic communication over distances of the order of, say, 2000 nautical miles has hitherto been considered very remote.

15 This invention relates to improvements which render possible telephonic transmission over long distances up to about 2000 nautical miles or greater.

20 In the case of telegraphic communication, a received current of the order of 10 microamperes is sufficient in most cases to give satisfactory working, and the variation of attenuation with frequency is relatively of 25 small importance as the range of frequencies required for intelligible signalling is comparatively small. For example, the attenuation of a typical submarine telegraph cable is such that a current of 10 microamperes is received when sending direct current reversals with 60 volts at a frequency of 30 33.5 ~ (cycles per second) and satisfactory signalling at a speed corresponding to this figure is obtained, in spite of the fact that at 35 twice the above frequency (i. e. at 67~) the received current is only 0.2 microampere.

Now for telephonic communication a received current substantially greater than 10 microamperes is necessary, as amplification 40 is limited by the degree to which the system can be balanced for two way working. Further, the band of frequencies necessary for the transmission of intelligible speech is very much wider than that used in telegraphy, 45 probably extending from 2 or 3 hundred to

between 2 and 3 thousand cycles. It is therefore evident that the diminution of received current relative to increasing frequency permissible in the example given for a telegraph cable is to be avoided in the case of a telephone cable. That is, an efficient telephone 50 cable must have a low attenuation to the mean speech frequency (usually taken as 800 or 1000~) and a small variation of this attenuation with frequency.

55 The attenuation per unit length of a cable is given approximately by the well known formula,

$$a = \frac{R}{2} \sqrt{\frac{C}{L}} + \frac{G}{2} \sqrt{\frac{L}{C}}$$

60 where R is the resistance in ohms, L the inductance in henries, G the leakance in ohms, and C the capacity in farads, all referred to unit length of the cable. The constants C and L do not normally vary appreciably with 65 frequency, and therefore the object of this invention is to make the variation of R with frequency as small as possible, and further to control G or to make the term

$$\frac{G}{2} \sqrt{\frac{L}{C}}$$

70 small compared with the first term

$$\frac{R}{2} \sqrt{\frac{C}{L}}$$

75 The invention is illustrated in the accompanying drawing.

According to this invention, a telephone 80 cable is loaded with tape which is not thicker than about .0015 inches of loading alloy having after heat treatment a high specific resistance and an initial permeability between 300 and 800.

85 Preferably the loading material consists of a tape of thickness about .001 inches applied and annealed in the manner described in U. S. Patent No. 1,691,309, issued to W. S. Smith, H. J. Garnett and J. A. Holden Nov. 90

13, 1928. The tape is conveniently about .03" wide but this dimension may be considerably varied. The specific resistance of the loading material is advantageously as high as possible compatible with the requisite permeability and convenient workability. A specific resistance of the loading material of, say, 100 microhms per centimetre cube combined with the thinness of the tape reduces eddy current loss to a very small proportion of the total resistance.

As an example, a conductor weighing 1100 lbs. per nautical mile and having a direct current resistance of 1 ohm per nautical mile is loaded with 2 layers of the .001" tape and annealed so as to give an inductance of 4.5 millihenries per nautical mile. The eddy current resistance at 1000 $\sim$ is 0.015 ohm and at 2000 $\sim$ 0.06 ohm per nautical mile. The result of applying the high resistivity loading material in more than one layer of 1 mil tape is thus to limit the variation of R with frequency to a comparatively small amount.

The composition of a suitable loading alloy is that described in the co-pending application of W. S. Smith, H. J. Garnett and J. A. Holden, Ser. No. 230,688, filed Nov. 22, 1927, but other compositions giving the requisite permeability and specific resistance after suitable heat treatment may be used.

With regard to leakance, no material has hitherto been found in which leakance, varies with frequency at a rate less than in direct proportion, and in most cases the variation with frequency is approximately in accordance with the law $G = an + bn^2$ where a and b are constants and n is the $\sim$. It is therefore necessary to reduce the intrinsic value of G to as low a value as is practicable.

It has been found that a leakance value of 2 microhms per cm. cube at 1000 $\sim$ at 75° F. can be obtained by using a mixture of gutta percha and/or balata treated so as to remove all protein, cellulosic matter and other impurities. For this purpose the raw material is dissolved in a suitable solvent, for example, benzene or petroleum spirit, and the impurities removed by sedimentation and decantation or by filtration, if necessary in the presence of known aids to these processes, after which the purified material is recovered, for example, by evaporation of the solvent or by freezing out. In some cases it may be necessary to remove the resin wholly or in part from the gutta percha or other material. This may be done by known methods before or after the purification described above. The particular composition of the mixture to be used is determined by reference to curves connecting leakance and other electrical properties, such as capacity, with composition. In certain cases it may be advantageous to add a small percentage of a suitable preservative, e. g. tannin, to the mixture.

The leakance of the cable will not, how-

ever, entirely depend on that of the gutta percha insulation alone. The electrical characteristics of the compound with which the interstices of the loaded conductor are filled before covering having been found to affect considerably the leakance of the completed core.

It is a well-known fact that the permeability of many magnetic materials at low magnetizing forces is greatly diminished by mechanical strain. This behaviour is shown very markedly by many magnetic materials of high initial permeability such as are suitable for the continuous loading of submarine telegraph and telephone conductors. It has been found that when a conductor, continuously loaded with such a magnetic material of high initial permeability, and covered in the ordinary way with gutta percha, is subjected to hydrostatic pressures of the order of those prevailing in ocean depths, the added inductance of the conductor is greatly diminished, probably as a result of strain produced in the loading material by the outside pressure reducing the permeability of the magnetic material.

The present invention further relates to a pressure equalizing medium with which the loading material is surrounded before the application of the outer covering or insulation, such medium serving as a fluid cushion for distributing the external pressures evenly over the conductor and thus prevent strains from being set up and thereby reduce this decrease in the inductance of the conductor.

A suitable compound, which does not change its physical condition at the temperatures and pressures encountered on the ocean bed, comprises a substantially non-volatile paraffin hydrocarbon, to which rubber, gutta percha, balata or the like may be added as a thickener. In some cases it may be advisable also to add materials such as resin adapted to increase the stickiness of the composition.

The paraffin hydrocarbons used in the preparation of the compound are viscous liquids or semi-solids at ordinary temperatures. The petroleum products commonly known respectively as petroleum jelly (soft white or yellow paraffin) and medicinal paraffin have proved to be very suitable bases for these compounds, and e. g. rubber is added until a material is obtained that will coat the copper conductor smoothly and flow into the interstices of the loaded conductor at ordinary temperatures and at the same time is sufficiently viscous not to be displaced from the loaded conductor during the process of covering with the gutta percha insulation, and that is still sufficiently fluid at the temperature of the water in great ocean depths to distribute the hydrostatic pressure uniformly over the magnetic material.

Suitable proportions of the ingredients are as follows:—

Example 1

	Parts	
5 Rubber	14	
Soft yellow		
Paraffin	86	

Example 2

	Parts	
10 Rubber	40	
Medicinal paraffin	60	

Example 3

	Parts	
15 Rubber	10	
Soft yellow		
Paraffin	67	
Medicinal paraffin	23	

Example 4

	Parts	
20 Soft yellow		
Paraffin	57	
Balata resin	40	
Crepe rubber	3	

25 The ingredients are mixed together by methods and in machines well known to those skilled in the art of rubber manufacture. In some cases, where as in Example 2, the proportion of rubber is high, it is advisable to 30 "break down" the rubber by mastication before adding the other ingredients. The proportions of the ingredients stated above are given merely by way of example and should not be regarded as limits.

35 The advantages of the compounds in accordance with the invention are that their viscosity can be varied between fairly wide limits to meet any particular case by altering the proportions of the ingredients and 40 also that their alternating current leakance and their dielectric constant are relatively low; moreover they have the properties essential to a pressure-equalizing medium, namely fluidity at low temperatures and high 45 pressures, high dielectric resistance, stability of chemical composition and physical state and inertness towards the gutta percha insulation, copper conductor and loading material.

50 Owing to their low dielectric constant, these compounds are also suitable for impregnating the fibrous insulation of telephone cables.

The breakdown resistance of these compounds is also exceptionally high, so that they 55 can be used with advantage for impregnating the insulation of power cables.

A cable according to this invention suitable for telephoning over a distance of about 2000 nautical miles may be constructed in the 60 following manner:—

The cable has a twin core, each conductor weighing about 2150 lbs. per nautical mile and having a direct current resistance of 0.05 ohm. The loading consists preferably of two layers of 1 mil

tape of permeability 750 giving a total inductance of 7 milli henries per nautical mile of loop circuit with an effective resistance of approximately 1 ohm per nautical mile at 1000 ~.

A covering on each core of 1100 lbs. per nautical mile of gutta percha prepared as above described gives a capacity of $.2 \mu F.$ and a leakance of about 4 microhms per nautical mile of the loop circuit in the laid cable. The attenuation under these conditions is .003 per nautical mile and the total attenuation over 2000 nautical miles including head and losses, would not exceed 8 at 1000 ~.

Owing to the low characteristic impedance of this cable (rather less than 200 ohms) and the low hysteresis loss of the loading material, such a type of cable is suitable for higher sending voltages than those normally employed, although experiment has shown that such increase may not be necessary.

What we claim is:—

1. A loaded signalling conductor suitable for the transmission of electric currents at audio and carrier frequencies, comprising a conducting member and a layer of loading material having a thickness not in excess of about 0.0015 inches and formed of an alloy having high specific resistance and a permeability below about 800 at low magnetizing forces.

2. A loaded signalling conductor suitable for the transmission of electric currents at audio and carrier frequencies, comprising a conducting member and a layer of loading material having a thickness not in excess of about 0.0015 inches and formed of an alloy having high specific resistance and a permeability between 300 and 800 at low magnetizing forces.

3. A loaded signalling conductor suitable for the transmission of electric currents at audio and carrier frequencies, comprising a conducting member and a loading tape having a thickness of 0.001 inches and formed from an alloy having high specific resistance and a permeability between 300 and 800 at low magnetizing forces.

4. A loaded signalling conductor suitable for the transmission of electric currents at audio and carried frequencies, comprising a conducting member and a loading tape having a thickness of 0.001 inches and formed from an alloy having specific resistance of the order of 100 microhms per centimeter cube and a permeability between 300 and 800 at low magnetizing forces.

5. A loaded signalling conductor suitable for the transmission of electric currents at audio and carrier frequencies, comprising a conducting member and a plurality of layers of loading material each layer having a thickness not in excess of about 0.0015 inches, said material being formed of an alloy hav-

ing high specific resistance and a permeability between 300 and 800 at low magnetizing forces.

6. A loaded signalling conductor suitable for the transmission of electric currents at audio and carrier frequencies, comprising a conducting member, and a loading tape having a thickness not in excess of about 0.0015 inches and formed of an alloy having high specific resistance and a permeability between 300 and 800 at low magnetizing forces, the whole being insulated with a material comprising gutta percha, treated to remove all protein, cellulosic matter, and other impurities.

7. A loaded signalling conductor suitable for the transmission of electric currents at audio and carrier frequencies, comprising a conducting member, a loading tape having a thickness not in excess of about 0.0015 inches and formed of an alloy having high specific resistance and a permeability between 300 and 800 at low magnetizing forces, an outer cover and a pressure equalizing medium consisting of a viscous paraffin hydrocarbon between said loading tape and the outer cover.

8. A loaded signalling conductor suitable for the transmission of electric currents at audio and carrier frequencies, comprising a conducting member, and a loading tape having a thickness not in excess of about 0.0015 inches and formed of an alloy having high specific resistance and a permeability between 300 and 800 at low magnetizing forces, the whole being insulated with a material comprising gutta percha, treated to remove all protein, cellulosic matter and other impurities, and provided with a pressure equalizing medium comprising mainly petroleum jelly between said insulation and loading tape.

9. A loaded signalling conductor suitable for the transmission of electric currents at audio and carrier frequencies, comprising a conducting member and a layer of loading material applied thereto and in which said loading material is surrounded with a congealed or viscous paraffin hydrocarbon which serves as a fluid cushion to distribute external pressure.

10. A loaded signalling conductor suitable for the transmission of electric currents at audio and carrier frequencies, comprising a conducting member and a layer of loading material applied thereto, and in which said loading material is surrounded with a congealed or viscous paraffin hydrocarbon comprising petroleum jelly which serves as a fluid cushion to distribute external pressure.

11. A loaded signalling conductor suitable for the transmission of electric currents at audio and carrier frequencies, comprising a conducting member and a layer of loading material applied thereto and in which said

loading material is surrounded with a pressure equalizing medium comprising a congealed or viscous paraffin hydrocarbon and a gummy thickener.

12. A loaded signalling conductor suitable for the transmission of electric currents at audio and carrier frequencies, comprising a conducting member and a layer of loading material applied thereto, and in which said loading material is surrounded with a pressure equalizing medium comprising a congealed of viscous paraffin hydrocarbon, and a thickener selected from the following group, viz.: rubber, gutta percha, and balata.
